(57) **CLAIM**

The ornamental design for a jewelry ring, as shown and described.

DESCRIPTION

FIG. 1 is a front perspective view of a jewelry ring from above;

FIG. 2 is a rear perspective view from below of the jewelry ring of FIG. 1;

FIG. 3 is a front view of the jewelry ring of FIG. 1;

FIG. 4 is a rear view of the jewelry ring of FIG. 1;

FIG. 5 is a view of the jewelry ring of FIG. 1 from one side;

FIG. 6 is a view of the jewelry ring of FIG. 1 from another side;

FIG. 7 is a top view of the jewelry ring of FIG. 1;

FIG. 8 is a bottom view of the jewelry ring of FIG. 1;

FIG. 9 is the view of FIG. 8 of the jewelry ring of FIG. 1 with section lines 10;

FIG. 10 is a cross section view of the jewelry ring of FIG. 1 taken at the section lines 10 shown in FIG. 9.

FIG. 11 is a front perspective view of a second embodiment of the jewelry ring from above;

FIG. 12 is a rear perspective view from below of the jewelry ring of FIG. 11;

FIG. 13 is a front view of the jewelry ring of FIG. 11;

FIG. 14 is a rear view of the jewelry ring of FIG. 11;

FIG. 15 is a view of the jewelry ring of FIG. 11 from one side; and,

FIG. 16 is a view of the jewelry ring of FIG. 11 from another side.

In this second embodiment, the top and bottom and sectional views are identical to those of FIGS. 7 and 8 and 9 and 10. In this second embodiment, the broken lines showing logos illustrate portions of the jewelry ring that form no part of the claimed design. In FIG. 9 the broken lines are shown for reference and form no part of the claimed design.
